UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed November 11, 1919. Serial No. 337,118.

To all whom it may concern:

Be it known that I, ALFRED G. F. KUROWSKI, a citizen of the United States, formerly a citizen of Germany, residing in Brooklyn Borough, in the county of Kings, city and State of New York, have invented certain new and useful Improvements in Typewriting Machines, of which the following is a specification.

10 This invention relates to typewriter-keys, and an object thereof is to improve the key-touch.

To this end, a feature of the invention consists in providing a construction of key, whereby there is relative movement between the key-top and the key-lever. This relative movement is normally resiliently resisted, or cushioned, preferably by a spring, interposed between the key-top and the key-lever.

15 Preferably, also, a socket is provided having a housing for the spring, the key-top being mounted on, or connected to, the socket in any desired manner.

20 Other features and advantages will herein-
25 after appear.

In the accompanying drawings,

Figure 1 is an elevational view of a portion of a key-lever, showing parts of my improvement in section.

30 Figure 2 is a view showing the several parts making up my improved key, separated from each other, so as to set forth clearly the detailed construction of each part; and

35 Figure 3 is a sectional view.

Referring to the drawings, 1 indicates a key-lever, having a cut-out portion 2 and a slot 3. Over said key-lever fits a socket 4, which has a semi-circular drawn-out portion 5, which acts as a housing for a compression-spring 6. The housing is provided with parallel portions 7, at its lower end, which snugly but slidably embrace the key-lever 1, and connected to, or mounted on, the upper 40 enlarged portion of the housing which forms a key-cup, is a key-cap 8, which holds in the key-cup the usual glass 9 and key-paper 10. In order to secure the key-cap to the housing, said cap may be provided with fingers 11, which may be bent under the housing, as shown in Figures 1 and 3. When the parts are assembled, the compression-spring 45 seats against the lower end 12 of the cut-out portion 2 in the key-lever 1, its upper end bearing against a plug 13, in the socket,

beneath the key-paper 10, so that the spring 6 acts between the key-lever 1 and the key-cap 8 to lift the entire key-top. Thus, the tendency of the spring is to hold the socket in the elevated position shown in Figures 1 and 3, the vertical movement of the socket, in obedience to the action of the spring, being limited by a pin 14, passing through openings 15 in the parallel portions 7 of the socket and through the slot 3 in the key-lever. The slot 3, of course, also limits the downward movement of the socket relative to the key-lever. By unbending the prongs on fingers 11, the cap 8, glass disk 9, key-paper 10, plug 13 and thrust-spring 6 may 50 all be removed from the socket 4, as shown in Figure 1, thereby enabling the spring 6 to be replaced by a new spring, should that become necessary.

Variations may be resorted to within the 55 scope of the invention, and portions of the improvements may be used without others.

Having thus described my invention, I claim:

1. In a typewriting machine, the combination with a key-lever having a recess extending downward from the upper edge thereof to serve as a chamber for a spring, of a sleeve fitted over the key-lever for sliding movement up and down thereon, a character plate or disk supported by and closing the upper end of the sleeve, a spring seated in the recess in the key-lever within the sleeve and bearing at its upper end against the character plate, and means for holding the character plate against upward displacement, by the spring, relative to the sleeve.

2. In a typewriter key, the combination with a key-lever, of a key-top comprising a socket adapted to fit on said key-lever and a cap on said socket, and a spring within the socket acting between the key-lever and cap for providing resiliently-resisted movement between said key-top and key-lever for cushioning the key-stroke, said cap being removable to allow removal of said spring from said socket.

3. In a typewriter key, the combination with a key-lever, of a key-top comprising a socket adapted to fit on said key-lever, a key-paper and key-glass in said socket, and a cap on said socket to hold said key-paper and key-glass in position, and a compression spring in the socket between the key-paper

and key-lever for providing resiliently-re-sisted movement between said key-top and key-lever for cushioning the key-stroke, said cap being removable to allow removal of 5 said key-paper, key-glass, and spring from said socket.

4. In a typewriter key, the combination with a key-lever, of a socket fitting on said lever, a key-paper and key-glass in the 10 upper end of said socket, a cap on said socket for holding said key-paper and key-glass in position, a housing in said socket, a spring in said housing bearing against said key-lever and socket, and a lost-motion connection between said socket and lever normally taken up by said spring.

5. In a typewriting machine, the combination with a key-lever having an upstanding end, of a key-top comprising a socket slid- 20 ably fitting over the upstanding end of the

key-lever for substantially vertical move-
ment thereon, said socket having an enlarged
upper end forming a key-cup, a key-paper
and a key-glass in the key-cup, said socket
forming a housing below the key-cup, a com-
pression spring in the housing between the
key-paper and the end of the key-lever, a
cap on the key-cup for receiving the thrust
of the spring and for retaining the key-
paper and the key-glass in the key-cup, and
a lost-motion connection between the socket
and the end of the key-lever normally taken
up by the spring lifting the key-top on the
end of the key-lever so as to cushion the key-
top on the key-lever. 25

ALFRED G. F. KUROWSKI.
